UNITED STATES PATENT OFFICE.

WINFIELD SCOTT ANDERSON, OF CINCINNATI, OHIO.

MOLDER'S LADLE.

SPECIFICATION forming part of Letters Patent No. 730,218, dated June 9, 1903.

Application filed January 5, 1903. Serial No. 137,766. (No model.)

To all whom it may concern:

Be it known that I, WINFIELD SCOTT ANDERSON, a citizen of the United States, residing in the city of Cincinnati, in the county of Hamilton and State of Ohio, have invented 5 certain new and useful Improvements in Molders' Ladles; and I do declare the following to be a clear, full, and exact description thereof, attention being called to the accompanying drawings, with the reference characters marked thereon, which form a part of this specification.

This invention relates to improvements in ladles of the kind used by molders in foundries 15 to pour the molten metal into the molds. Such ladles consist substantially of a pot, being the receptacle which holds the molten metal, and is usually of metal lined with suitable fireproof material, like fire-clay. They 20 consist, further, of a handle made of an iron rod and of means whereby the pot is connected to the handle and whereby it is also held in proper position for carrying the metal. These means consist of a circular ring or band on 25 the lower end of the handle, with which it usually forms one piece and within which ring the pot hangs. This latter is slightly tapering on its outside, for which reason it fits snugly within the ring and remains readily in 30 position without any special means for connecting it. A ladle so constructed is subject to several objections. The handle, being an iron rod, the thickness of which is limited to keep its weight down, bears quite heavily 35 upon the hand under the weight of the metal carried, exerting a cutting pressure. It furthermore becomes quickly hot, and has therefore to be continually cooled off to permit of it being used. These objections I overcome 40 by providing a wooden handle, which does not become hot and can be made thicker, so as to fill the grasp of the hand more evenly, and without being heavier by reason of such increased thickness, which would otherwise 45 be the case if the thickness of the iron handle would be increased. Another objection is the fixed size, diametrically, of the band which receives and encircles the pot in view of the fact that the pots as to diameter are not strictly 50 alike. Therefore if these variations exceed

certain limits the particular pot cannot be used in connection with a certain handle, while variations within these limits would cause such a pot, by reason of its taper, to either sit up higher or lower within this band. 55 This is not immaterial; however, since a position either too high or too low interferes in both cases with the proper manipulation of the ladle for tilting it for pouring. This latter objection I overcome by making this band 60 adjustable to suit within certain limits the size diametrically of the particular pot to be used, permitting also a pot of a certain size to be set up higher or lower within this band to suit the convenience of the particular 65 molder.

The invention consists of a ladle—that is, of the pot-holder and handle on it—constructed to overcome the objections stated, and as the same, with its parts and manner of use, is described in the following specification, with claims annexed, and also as illustrated in the accompanying drawings, in which—

Figure 1 is a perspective view of my improved ladle. Fig. 2 is an enlarged view of the 75 lower part of it, being more particularly the member which holds the pot, parts being shown in section. Fig. 3 shows the same parts before adjustment. Fig. 4 is a perspective view of these parts, showing them slightly 80 modified. Fig. 5 is a view of the sheet-steel blank out of which the pot-holding band and its shank is made, it being shown at a reduced scale and provided with the reference characters corresponding to the particular parts 85 in the completed device.

In the drawings, 10 indicates the handle formed at its upper end into a grip 11 and all made of wood. This material being lighter than iron permits an increase in thickness 90 without rendering the implement heavier and avoids the objectionable effects of a thin iron rod upon the hands. Neither does it become hot, like is the case in such an iron rod, and which for this reason has to be continually 95 cooled to permit handling.

12 is the iron pot provided with a fireproof lining 13 and hanging within a band 14, it remaining in position by reason of a slight taper on its outside. By means of a tubular 100

shank 15 this band is held to the wooden handle, one end of which it receives, the connection being completed by means of nails, screws, or bolts 16. Band 14 and shank 15 are of one piece of metal, preferably sheet-steel of sufficient thickness, and to prevent any heat absorbed thereby from being transmitted to the wooden handle a non-conducting and fireproof lining 17 is interposed. A lining of asbestos around the inside of the tubular shank 15, which separates the wood from the iron, is preferred.

As before stated, the pots are not all of the same size, so that if the variation is too much a certain band of fixed size may not be capable of receiving a certain pot or such pot may sit up too high or low in the band. To provide for all such contingencies, band 14 is left open, its separated end 14^a being of a length which permits adjustment of the band diametrically to fit around a certain pot if required and leaves also in addition always sufficient surplus after so adjusted to permit overlapping of these open ends and attachment thereto of means whereby they are finally secured to each other to close and lock the band around the pot after its adjustment thereto. To so hold these ends of band 14 at a certain position with reference to each other after adjustment, a bolt or pin 18 is used, passing through one of a number of perforations 19 in each of the ends, which openings are brought to register with each other. To hold these overlapping ends snugly on each other, a sliding loop 21 may be used for each end, or one for one end, as shown in Figs. 1, 2, and 3, the other end being provided with equivalent means in shape of lugs 22, which are bent over and down on the other end. In Fig. 4 these lugs are provided on both ends, doing away with a sliding loop. Where such lugs are used, they form integral parts of the combined band and shank structure and are provided for in the blank, as shown in Fig. 5. The parts of the band remain readily in position, the overlapping ends being held on each other by loops 21 or lugs 22, while they are held endwise on each other by means of pin 18. This latter, having a head on its inner end, is readily held in place by pot 12 when the same is in position within the band. If necessary, however, or to prevent it from being lost when the pot is not within the band, loop 21 may be shoved over it, as shown in Fig. 2. A nut 23 may be used for such purpose, as shown in Fig. 4. Fig. 5 shows the sheet-steel blank out of which band 14 and shank 15 are shaped, it being in this case intended for the form shown in Figs. 1, 2, and 3, where one of the ends has integral lugs 22. As will be seen, the wooden handle prevents burning of the hands and, being thicker than the iron rod now used, does not exert a painful pressure upon the hands.

55 The adjustable band may within certain

limits be fitted to any pot, and any particular pot may be set up higher or lower to suit convenience in dipping or tilting to facilitate pouring. The integral connection between band and shank simplifies the construction and obviates a weak point at the joint.

It is clear that as far as the feature of its adjustment is concerned the pot-holding band is not dependent on the kind of handle or its material, and as far as such handle is concerned the shank or a continuation of it is the full equivalent of a handle with reference to the band.

Having described my invention, I claim as new—

1. In a molder's ladle, the combination of a handle, a circular pot-holding band thereon, which is open and has its separated ends overlapping, perforations in these ends adapted to receive a locking-pin to hold these ends against movement in endwise direction and means to hold them sidewise one on the other, but in a manner to leave them free to slide endwise.

2. In a molder's ladle the combination of a handle, a circular pot-holding band consisting of two branches which project from one end of the handle and have their free ends overlapping and means engaging these ends for the purpose of locking them to each other.

3. In a molder's ladle, the combination of a shank adapted to receive a handle, a circular pot-holding band consisting of two branches projecting integrally from the end of the shank at diametrically opposite points thereof and after bent to assume the circular shape overlap at their free ends and means to hold these ends one to the other, to form a closed circle to fit a pot of a certain size.

4. In a molder's ladle, the combination of a handle, a circular pot-holding band thereon which is open and has its separated ends overlapping, perforations in these ends adapted to receive a locking-pin to hold these ends against movement in endwise direction and means to hold this pin within the perforations it occupies.

5. In a molder's ladle, the combination of a handle, a circular pot-holding band thereon which is open and has its separated ends overlapping, perforations in these ends adapted to receive a locking-pin to hold these ends against movement in endwise direction and lugs on one end projecting over the edge of the overlapping other end to hold them sideways on each other.

6. As an article of manufacture, a holder for a molder's ladle-pot consisting of a shank adapted to receive an independent handle, a circular pot-holding band which consists of two branches projecting integrally from one end of this shank with their free ends overlapping and means to lock these ends to each other.

7. The blank to form integrally an endwise-

open band and a connected shank, the first adapted to be fitted around a molder's ladle-pot so as to support the same when said ends are locked to each other, the other intended to form a shank adapted to receive a ladle-handle, said blank consisting of the elongated parts 14 which form the separated ends 14^a of the band and of the part 15 out of which

the shank is formed and from which part the former two parts project. 10

In testimony whereof I hereunto set my signature in the presence of two witnesses.

WINFIELD SCOTT ANDERSON.
